BANDIT OR BURGLAR TRAP

Chester L. Goldsmith and Bert F. Wood,
Winchester, N. H.

Application September 6, 1934, Serial No. 742,978

3 Claims. (Cl. 20—1.01)

This invention relates to apparatus for protecting banks against bandits and other malefactors and the object is to provide an apparatus which may be set in motion by any member of the bank's force and will operate with certainty to effectually bar the egress of evil-disposed persons who may have found their way into the bank. An apparatus embodying the invention is illustrated in the accompanying drawings and will be hereinafter fully described, the novel features being defined in the appended claims.

In the drawings:

Figure 1 is a vertical section of a portion of a bank building having our apparatus installed therein.

Figure 2 is a horizontal section on the line 2—2 of Figure 1.

Figure 3 is a section on the line 3—3 of Figure 1.

Figure 4 is a detail view of a releasing treadle. Figures 5 and 6 are detail elevations of the doors which form parts of the apparatus.

Figure 7 is a detail view of another releasing treadle.

The reference numeral 1 indicates a bank lobby and 2 designates a counter extending along one side of the lobby, there being a cellar or basement 3 beneath the lobby and a doorway 4 affording entrance to the lobby. Tracks 5 are set in the walls at the sides of the doorway and a vertically movable door 6 is slidably fitted to these tracks, said door consisting of a frame 7 and rods or bars 8 secured rigidly in and extending between the top and bottom of the frame. The door is normally lowered in the cellar or basement with its top in a slot in the floor of the doorway flush with the floor, and a latch 9 is provided near the floor of the cellar in position to engage over a projection 10 in the form of a trip, on the door at the bottom thereof to hold the door in its lowered position. The latch is pivoted on a bracket 11 which may be secured upon some fixed support, as a wall or column in the cellar, and it will be noted that the pivot is near one end of the latch, the short end of the latch engaging over the projection 10 and being beveled or tapered on its upper side to provide a cam to permit the projection to ride easily thereover when the door is descending. The latch is yieldably held in its active position by a contractile spring 12 suitably anchored at one end and having its opposite end connected with the latch by a cable 13 which is secured upon the outer side of the latch or latch arm, as at 13'. Pivoted between its ends upon the bracket 11 is an upright keeper 14, the lower end of which forms a hook 15 engageable under

the free end of the latch, as shown in Figure 1, to maintain the latch in engagement with the projection. The upper end of the keeper is provided with an eye 16 extending through an arcuate slot 17 in the bracket 11, as shown in Figure 5 3, and a cable 18 has one end attached to said eye and its opposite end attached to a contractile spring 19 anchored near the spring 12, whereby the keeper is yieldably held in the position shown in Figure 1 to engage the latch. Also attached to 10 the eye 16 is a cable 20 which extends away from the cable 18 to pass around a pulley 21 on the bracket, then back across the bracket to and under a pulley 22 on the adjacent wall, and then up to and over a pulley 23 on the cellar ceiling. From 15 the pulley 23, the cable is carried to a treadle 24 arranged back of the counter where it may be easily operated by a teller or other employee. The treadle is shown in detail in Figure 4 and comprises a stem slidably mounted in and extending 20 through the floor of the banking room, a spring 25 between the floor and the head of the treadle yieldably holding the treadle raised and a suitable stop 26 on the treadle below the floor limiting the upward movement. A bell crank lever 27 is 25 mounted adjacent the treadle and has one end attached to the cable 20, the opposite end of the lever being formed with a slot 28 receiving a pin or stud 29 on the treadle. It will now be understood that if the treadle be depressed, the bell 30 crank lever will be rocked to exert a pull through the cable 20 to rock the keeper out of engagement with the latch whereupon the door will be free to rise.

A weighted means including a platform 29' 35 carrying weights 30 is mounted for slidable movement on a pair of upright guide posts 31, and a cable 32 connects the platform with the lower end of the door 6, the cable 32 being secured to the door through the medium of an eyed member 32' shown in Figure 5, and the intermediate portion of the cable is trained about suitable pulleys, with the result it will be seen that when the door is lowered, the weighted means will be suspended near the ceiling as shown by dotted lines in Figure 1. The platform has secured thereto and rising therefrom a pair of sleeves 30' that are threaded on the uprights to act as guiding means for the platform and the weights 30 have recessed sides to receive the sleeves therein, as shown in 50 Figure 1. When the latch is released, the weighted means will drop, as shown in full lines in Figure 1, and the door will be pulled up to close the doorway 4. The latch will yield to the upward movement of the door, thus increasing the tension of 55

the spring 12 which will return the latch to normal position as soon as the projection 10 has cleared the latch. When the door descends, the latch will be rocked in the opposite direction, the 5 spring acting as before. When the treadle is released, the spring 19 will act to return the keeper to its normal position, and it will be readily noted that the keeper will prevent movement of the latch to release the door but will not interfere with the movement of the latch to accommodate and engage the descending door.

Generally, there is a table or desk 33 in the bank lobby for the use of a watchman or other attendant. We provide a treadle 34 under this 15 table which is connected to one end of a lever 35 suitably fulcrumed between its ends on the cellar ceiling and having its opposite end attached to a branch cable 36 which is united with the cable 20 so that depression of the treadle 34 20 will cause the same action as depression of the treadle 24.

Formed on the side edge of the door, at its lower end, are downwardly pointing ratchet teeth 37, and a pawl 38 is arranged adjacent the door near 25 the ceiling of the basement to engage the teeth and lock the door in its raised position. The pawl is pivoted at its lower end and inclines toward the door so that the teeth may ride under the pawl which will automatically drop under the 30 ratchet teeth, being pressed thereto by a spring 39 arranged in any suitable convenient manner. Between the pawl and the door is a crank arm 40 on the inner end of a rock shaft 41 which may be mounted in any convenient manner upon a 35 fixed support, as a structural element of the building, the side of the crank arm 40 bearing against the side of the pawl and a second crank arm 42 being provided on the outer end of the shaft. When force is applied to the crank 42 to rock the 40 shaft, the crank 40 will be rocked against the pawl to swing the latter out of engagement with the door, thereby permitting the door to be pushed down to its lowered position. A cable 43 is attached to the crank 42 and extends therefrom 45 to a crank 44 on the bolt or tumbler of a locking mechanism 45, the key to which is to be held by the police force or other authorities. The locking mechanism may be of any approved design and is illustrated in a conventional manner only. As 50 shown in Figure 2, the locking mechanism is disposed in a compartment 46 at one side of the main doorway 4 and the entrance to this compartment is to be controlled by the police.

A horizontally movable door 47 is arranged to 55 roll across the doorway 4 at the outer side of the door 6, said door 47 consisting of bars 48, movable through guide openings provided therefor in the wall of the doorway 4, and a post 49 connecting the inner ends of the bars and equipped with a 60 roller 50 at its lower end to facilitate its travel. A cable 51 is attached to the post 49 and extends therefrom longitudinally of the door to a pulley 52 on the wall of the compartment 46, then around said pulley and to a pulley 53 on the ceiling of the room or compartment which contains the mechanism connected with the door 47 for operating the same. The cable 51 is attached to a weighted means including a platform 52' carrying weights 54, similar to the weights 30 and 65 the platform is slidably mounted on upright guide posts 55, with sleeves 30' secured thereto and rising therefrom for guiding the platform on the uprights. Buffer springs 56 surround the posts 55 and are arranged on the floors beneath both 70 platforms to cushion the impact thereof. On the 75

post 49 is a projection or trip 57 which, when the door is retracted, is engaged by a latch 58 so that the door will be held in the open retracted position, and it will be readily understood that if the latch be released, the means including the 5 weights 54 will at once drop and project the door across the door opening.

It will be noted that the latch 58 is disposed nearly vertically and is pivoted near its lower end, its lower shorter arm being engaged with the 10 catch 57 and a spring 59 acting to maintain the engagement between the latch and the catch. The latch is pivoted upon a bracket or panel 60 and the spring is disposed above the panel and connected with the latch by a cable 61 as at 61'. 15 A keeper 62 is pivoted between its ends upon the panel 60 above the latch and has its end adjacent the latch formed with a hook or shoulder 63 to be engaged by the upper end of the latch which will be thereby held against rocking. The keeper 20 is also provided with an eye 64 at its shouldered end to which a cable 65 is attached so that if a pull be given the cable, the keeper will be lifted out of engagement with the latch and the weight 54 will at once act, the upward movement of the 25 keeper being limited by stop pins 66, 67 on the panel above the keeper. The cable 65 extends up from the keeper to and over a pulley 68 and to a trip lever 69 to which it is connected by a spring 70, as shown. The trip lever is pivoted between 30 its ends within an opening 71 in the wall of the main doorway, and it will be readily noted that both arms of the lever are curved. The free end of the trip lever is normally in the path of the vertical door 6 so that as the door 6 nears the 35 upper limit of its movement, its side edge will ride over the free end of the trip lever and rock the lever to pull upon the cable 65 thereby lifting the latch as described, whereupon the door 47 will be projected across the door opening.

To the end of the keeper 62 remote from the cable 65 is attached a cable 72 which is held taut by a spring 73 above it, and attached to and extending downwardly from said end of the keeper are cables 74 which pass around suitable guide 45 pulleys to treadles 75 located at convenient or strategic points in the banking room and corresponding in all essential respects to the previously described treadle 24. By depressing a treadle 75, the horizontal door may be operated to close the 50 main doorway, even though the vertical door should fail, but generally the vertical door will operate and will automatically set the horizontal door in motion.

The door 47 has rearwardly projecting ratchet 55 teeth 76 on its upper edge and a pawl 77 is pivotally mounted above the door to drop into engagement with one of the teeth when the door is closed to thereby lock the door closed. The bolt of the lock 45 is provided with a crank arm 78 at its 60 inner end and a pin 79 on said crank arm extends under the pawl 77 so that when the lock is opened the pawl 77 will be rocked up out of engagement with the ratchet teeth of the horizontal door simultaneously with the rocking of the pawl 65 38 out of engagement with the vertical door. The doors may then be pushed back into the open positions.

From the foregoing description, taken in connection with the accompanying drawings, it will 70 be seen that we have provided an efficient apparatus whereby the escape of bandits from a bank will be prevented. The operating mechanism is concealed and, therefore, cannot be put out of order by the outlaws, and will operate silently 75

and automatically when a releasing treadle is depressed.

Having described our invention, what we claim is:

- 5 1. In protective apparatus, vertically and horizontally movable doors, means for holding the doors in open position, means tending constantly to close the doors, means to release the holding means and including automatic releasing means for the horizontally movable door actuated by the vertically movable door, means to automatically lock the doors in closed position, and means to release said locking means.
- 10 2. In a protective apparatus for a bank or the like, having an entrance, vertically and horizontally movable doors for closing said entrance, means for holding the doors in open position,

means tending constantly to close the doors, means to release the holding means, means to lock automatically the doors in closed position, and means operable from the exterior of the bank or the like to release said locking means. 5

- 15 3. In a protective apparatus for a bank or the like, having an entrance, vertically and horizontally movable doors for closing said entrance, means for holding the doors in open position, means tending constantly to close the doors, 10 means to release the holding means, means to lock automatically the doors in closed position, and manually operable means to release said locking means.

BERT F. WOOD.

CHESTER L. GOLDSMITH.
